APPARATUS FOR FINISHING FABRICS

Clarence T. Graham, North Attleboro, Mass., assignor, by mesne assignments, to Defiance Manufacturing Company, Barrowsville, Mass., a corporation of Massachusetts

Application October 21, 1938, Serial No. 236,148

2 Claims. (Cl. 91—51)

This invention relates to apparatus for finishing fabric. It is particularly applicable to fabric that consists of a ground and raised pattern or figure forming portions that are engaged with the ground and extend from one side, the obverse side, thereof.

As an example of such a fabric there is at the present time on the market a marquisette which consists of a ground and with which rovings or 10 yarn are engaged and extend from the obverse side of the ground to form a dotted fabric which has become known in the trade as fluffy dot fabric. In this type of fabric the fluffy dots retain a fluffy appearance while the ground is 15 finished as for instance by starching.

The fabric is completely woven with the ground and the dots in the weaving mills and is then finished in the weaving mills so that the problem involved is application of the finishing material 20 to the ground of the fabric without applying the finishing material or permitting the finishing material to reach the raised pattern or figure forming portions or fluff dots and in fluffing these dots.

25 In the drawing:

Figure 1 is a more or less diagrammatic view of an apparatus; and

Figure 2 is a fragmentary perspective view of the applicator for the finishing material; and

30 Figure 3 is a fragmentary view of the applicator roller for the liquid finishing material.

Describing now the apparatus, it includes a roller 1, which is rotatably mounted within a container 2 for rotation within a supply of liquid 35 finishing material and which may be driven by suitable means such as a motor 3 through a power transmission element 4. If it is desired this motor may be a variable speed motor so that the speed of rotation of the roller may be varied 40 or the speed of rotation of the roller may be varied by the use of other well known driving means. Spaced from the roller 1 is a drying chamber 5, through which a tenter frame 6 passes, and in which it is operated in the usual 45 manner. This chamber 5 may be heated by any suitable means, such as hot air.

Within the drying chamber 5 a platen 7 is 50 located, over which the fabric which is indicated in the drawing by the reference number 8 passes. Above this platen a manifold 9 is located, and is connected through a pipe 10 to a source of fluid under pressure, such, for instance, as steam. The steam is adapted to be projected 55 downwardly against the fabric 8 as it travels

over the platen, orifices 11 being provided for that purpose.

Associated with this mechanism is a rotatable brush 12, which consists of a cylinder having barbs 13 extending from its peripheral face, 5 which are adapted to engage the raised pattern or figure forming portions of the fabric and operate above a platen 14, which I have shown as triangular in form, and over the apex of which the fabric passes. These barbs 13 may be of any 10 suitable material, but I have found a curved steel wire to be admirably adapted for the purpose. This brush 12 may be rotated at a variable speed by a suitable mechanism as, for instance, a 15 variable speed motor 15.

If desired, a rotatable cleaner 16 may be associated with the brush 12, which cleaner is of substantially the same construction as the brush, to remove any material that accumulates in the brush during its operation. This cleaner 16 may 20 be driven from the motor 15.

Also associated with this mechanism is a stationary brush 17, the barbs of which extend diagonally in a direction opposite to the direction 25 of travel of the fabric, so as to engage the pattern or figure forming portions and raising them from the ground and giving them a fluffed-up attitude.

The cylinder 1 extends substantially the entire width of the fabric as does also the brush 12, the 30 manifold 9, the platen 14 and the platen 14.

This roller 1 is provided with grooves that extend in a longitudinal direction in relation to the cylinder and on its peripheral face, which insures the carrying of a sufficient amount of 35 the liquid finishing material in the supply of the container 2 to the reverse side of the fabric.

In the drawing I have illustrated one form of this cylinder which includes applicator surfaces 18 which are separated by longitudinal grooves 19, both the surfaces and the grooves extending substantially from end to end of the cylinder, or at least to an extent sufficient to apply the liquid 40 finishing material to that portion of the fabric to which it is desired to apply it.

These grooves 19 extend preferably somewhat tangentially of the roller 1, rather than radially for a purpose which will later appear, and, if desired, their depths may be varied by placing 50 therein removable fillers 20, the effect of this variation being that the quantity of liquid finishing material carried by the grooves may be varied as desired with the result that the amount of liquid finishing material applied to the fabric 55 may be controlled.

In operation the fabric, with the pattern or figure forming portions extending from the obverse side thereof, is moved longitudinally from a supply 21 by the tenter frame 6 or by any other means. As the fabric passes over the roller 1 with the reverse side of the fabric in contact with the peripheral face of the roller, the roller is rotated either in the direction indicated on the drawing by the arrow, or, if desired, in the opposite direction. When rotated in the direction indicated by the arrow as the grooves 19 are submerged in the liquid finishing material, the material fills the grooves and coats the applicator surfaces 18. As the grooves move upwardly 15 above the surface of the liquid finishing material, the liquid is spilled out of the grooves over the applicator surfaces 18, so that there is a continuous supply of the liquid finishing material to the applicator surfaces 18, and the amount of 20 this supply may be governed by any suitable means, such as, for instance, the fillers 20. As the fabric continues to move beyond the applicator roller 1, it enters the drying zone 5, where the finishing material is dried. The relationship between the speed of travel of the fabric, the amount of liquid finishing material applied to a unit area of the fabric, and the time intervening between the application of the finishing material to the fabric and its entrance into 30 the drying zone is such that the penetration of the liquid finishing material into the fabric will be confined to the ground of the fabric or to the ground and whatever portion of the raised pattern or figure forming portions is desired. The 35 result of this of course is that the ground fabric is given the desired hand while the original condition of the raised pattern or figure forming portions is not substantially changed. As the fabric passes through the drying zone 40 the pattern or figure forming portions are subjected to a blast of fluid under pressure which fluffs the pattern or figure forming portions and gives them a fluffy or fuzzy appearance. This fluffing of the pattern or figure forming 45 portions may be enhanced by the engagement of a brush such as 17 with said portions, and also by the operation of the rotary brush 12, the barbs of which engage the raised pattern or figure

forming portions, separating them and fluffing them up.

These brushes 17 and 12 may operate upon the fabric either before or after the application of the finishing material to the fabric. Both may operate before the application of the finishing material, or both may operate after the application of the finishing material. On the other hand, either may operate before the application of the finishing material, while the other operates after the application of the finishing material. Either or both of these brushes may operate in conjunction with the fluid pressure fluffer 11 or the fluid pressure fluffer may be dispensed with.

What I claim is:

1. In a machine for finishing fabric which includes a ground and raised pattern or figure forming portions on the obverse side thereof, to produce a fabric that has a finished ground and 20 unfinished pattern or figure forming portions, an applicator roller having grooves extending generally longitudinally in the face thereof and adapted to carry liquid finishing material, means for rotating said roller, means for drawing the 25 fabric over said roller with the reverse side of the fabric in position to receive the liquid finishing material from said grooves, means carried by the roller for reducing the size of the grooves, and means for supplying the grooves with liquid 30 finishing material.

2. In a machine for finishing fabric which includes a ground and raised pattern or figure forming portions on the obverse side thereof, to produce a fabric that has a finished ground and 35 unfinished pattern or figure forming portions, an applicator roller having grooves extending generally longitudinally in the face thereof and adapted to carry liquid finishing material, means for rotating said roller, means for drawing the 40 fabric over said roller with the reverse side of the fabric in position to receive the liquid finishing material from said grooves, means for varying the capacity of the grooves, said means for varying the capacity of the grooves including fillers 45 removably mounted in said grooves, and means for supplying the grooves with liquid finishing material.

CLARENCE T. GRAHAM.
